UNITED STATES PATENT OFFICE

FRANCIS H. GRIFFITHS, OF YONKERS, NEW YORK, ASSIGNOR TO THE RELIABLE AUTOMATIC SPRINKLER COMPANY, INC., OF NEW YORK, N. Y., A CORPORATION OF NEW YORK

ACCELERATOR FOR DRY-PIPE VALVES

Application filed October 26, 1923. Serial No. 670,859.

This invention relates to accelerators for dry-pipe valves and particularly to that type of accelerator which is constructed to operate upon a slight quick reduction of the pressure in the sprinkler system, such as would result from the giving way of a sprinkler head, to admit fluid under pressure to the intermediate or neutral chamber between the water valve and the air valve thereby to partially neutralize the pressure of the air against the air valve and to accelerate its opening movement.

One of the objects of the present invention is to provide a novel accelerator which is constructed so that the force which opens the valve that controls the supply of fluid under pressure to the intermediate chamber is secured from a weight, spring or its equivalent that is normally latched in its inoperative position but which is released upon a slight rapid fall in pressure in the system.

Other objects of the invention are to provide a novel construction in which the auxiliary valve is given a hammer-like blow to open it whenever the accelerator operates thus ensuring a proper opening of the valve even though the latter should be stuck to its seat.

Still other objects of the invention are to improve generally accelerators in various ways all as will be more fully hereinafter set forth and then pointed out in the appended claims.

In the drawings, wherein I have illustrated a selected embodiment of my invention, Fig. 1 is a view illustrating a dry-pipe valve partly in section and showing the accelerator connected thereto;

Fig. 2 is a vertical sectional view through the accelerator;

Fig. 3 shows a modification.

Fig. 1 indicates a dry-pipe valve of any suitable or usual construction, it comprising a casing having a water inlet 2, and an outlet 5 leading to the system, a pivotally-mounted water valve 3 for closing the water inlet, and a pivotally-mounted air valve 4 which is subjected to the air pressure in the system and which operates to hold the water valve closed, said casing having an intermediate or neutral chamber 6 between the water valve and the air valve. The intermediate chamber 6 nor-

mally has atmospheric pressure therein and the air valve 4 is of sufficient size so that the pressure thereagainst of the air in the system will serve to hold the water valve closed against the water pressure. 55

The accelerators of the type in which this invention belongs are constructed so that when there is a slight quick reduction of pressure in the system, such for instance, as would occur upon the giving way of a sprinkler head, fluid under pressure will be admitted to the intermediate chamber 6 thus building up a pressure against the under side of the air valve and accelerating its opening movement. 60

In the construction herein shown this accelerator comprises a casing 7 which is separated into two chambers 9 and 10 which have communication with each other through a small leak port only. In the present construction this leak port, which is indicated at 11, is formed in the head 12 of a sylphon bellows device 13 which is carried by the partition 14 separating the chambers, the latter having the opening 15 therein communicating with the interior of the sylphon-bellows. 75

The chamber 9 is normally in communication with some source of fluid pressure which may be either the air pressure in the system or the water pressure in the inlet pipe. In the construction shown in Fig. 1 the chamber 9 is normally in communication with the air pressure in the system and for this purpose it is connected to the discharge 5 through a pipe 16. As the result under normal conditions the same air pressure will obtain in the chamber 9 as exists in the sprinkler system and because of the small port 11 this same pressure will normally exist in the chamber 10 so that the head 12 will be in a balanced condition. 80 The chamber 9 is also connected to the neutral chamber 6 through a pipe 17 and an auxiliary valve 18 is employed for normally closing the passage through the pipe 17. Under normal conditions, therefore, the chamber 9 is in communication with the system but the communication between the chamber 9 and the neutral chamber 6 is closed by the valve 18. 85

In accordance with this invention I have provided an automatically-operative valve- 100

actuating means for opening the valve 18 which is normally latched in its inoperative position but which is released whenever there is a slight quick fall in pressure in the system, such as would result from the giving way of a sprinkler head. This automatically-operative means for opening the valve 18 may be a weight or a spring or any other similar device.

10 I have herein shown a weight 19 for this purpose which is positively held in its operative position. The weight has a stem or hanger 20 rising therefrom which is adapted to be supported on a support 22 that is herein shown as pivoted at 23 to the bracket arm 24. The support 22 is normally held in the position shown in Fig. 1 by means of a latch 25, said latch being maintained in its operative position by means of a spring 26.

20 The valve 18 is pivotally carried by a lever 27 which in turn is pivoted at 28 to the bracket member 24 and said lever is shown as acted on by a spring 29 which normally holds the valve 18 closed. The lever 27 has an arm 30 extending therefrom which is situated to be engaged by the portion 31 of the hanger when the weight falls, due to the withdrawing of the latch 25. The construction is such that when the weight is held in its raised position by the latch the loop or portion 31 of the hanger is situated a considerable distance above the lever 27. When, however, the latch 25 is withdrawn from beneath the member 22 then the weight may fall and in its downward movement the part 31 of the hanger is brought against the lever 27 with a hammer-like blow thus opening the valve 18 and allowing fluid under pressure to flow from the chamber 9 to the intermediate chamber.

40 A construction is provided which becomes operative upon a slight rapid fall in pressure in the system, such as would result from the giving way of a sprinkler head, but which will be inoperative upon a slow decrease in pressure such as might occur by reason of a slow leak in the system, for withdrawing the latch, thus allowing the weight to fall and open the valve 18.

50 The latch 25 is connected to the head 12 of the sylphon-bellows in such a way that when said head moves downwardly, due to an unbalancing of the pressures in the chambers 9 and 10, the latch will be withdrawn from engagement with the arm 22.

55 Said latch is shown as pivotally connected at 34 to one arm of a bell crank lever 32 which in turn is pivoted at 33 to the bracket 24. The other arm of the bell crank lever is connected to the head 12, and thus a downward movement of the head 12 will operate through the bell crank to retract the latch 25.

Under normal conditions the pressure in the two chambers 9 and 10 will be equalized because of the presence of the leak port 11 and the latch 25 will thus be held maintained in

its operative position by the spring 26. If there is a quick drop in pressure in the system due to the giving way of a sprinkler head then the pressure in the chamber 9 will be correspondingly reduced but the pressure in the chamber 10 will be reduced only slowly due to the smallness of the aperture 11. As a result the pressures against the opposite sides of the head 12 will be unbalanced and the latter will move downwardly thereby operating through the lever 32 to withdraw the latch 25 from engagement with the arm 22. This releases the weight 19 which falls and by its engagement with the lever 27 opens the valve 18 thus allowing air under pressure in the chamber 9 to be delivered to the intermediate chamber 6 which results in accelerating the opening movement of the air valve 4.

An advantage of this construction is that when the accelerator operates the valve 18 is given a hammer-like blow by the falling weight 19 with the result that any tendency for the valve to stick is instantly overcome and the proper opening of said valve is ensured.

An important feature of the invention is that the force necessary to open the valve 18 is not derived directly from the movement of the member 12 due to the unbalancing of the pressures thereagainst but is derived from the falling weight 19.

Instead of connecting the chamber 9 with the system as shown in Fig. 1 this chamber may be connected with the water supply pipe as shown in Fig. 3, in which case the fluid under pressure which is admitted to the intermediate chamber will be water from the water main rather than air from the system. The operation of the device, however, will be the same in either instance.

I claim:

1. An accelerator for dry pipe valves comprising a casing, a sylphon bellows within the casing dividing the latter into two chambers, said sylphon having a restricted orifice forming a restricted communication between the chambers, means connecting one chamber to the system side of a dry pipe valve and also connecting said chamber to the neutral chamber of said valve, a valve normally closing the latter connection, a weight which by its falling movement opens the valve, means including a sliding spring-pressed latch for normally holding the weight elevated, and a connection between said latch and the sylphon bellows, whereby a reduction of pressure on the system side of the dry pipe valve will cause the sylphon bellows to actuate the spring-pressed latch and release the weight.

2. An accelerator for dry pipe valves comprising a casing, a sylphon bellows within the casing dividing the latter into two chambers, said sylphon having a restricted orifice forming a restricted communication between

the chambers, means connecting one chamber to the system side of a dry pipe valve and also connecting said chamber to the neutral chamber of said valve, a valve normally closing the latter connection, a sliding spring-pressed latch connected to said bellows, a pivoted weight-supporting member having its free end normally engaging said latch, and a weight normally supported by said weight-supporting member and which by its falling movement opens said valve, whereby when a reduction of pressure on the system side of the dry pipe valve occurs the bellows will withdraw the latch from the weight-supporting member and thus release the weight.

3. An accelerator for dry pipe valves comprising a casing, a sylphon bellows in said casing and separating the latter into two chambers, means connecting one of the chambers to the system side of the dry pipe valve, other means connecting said chamber to the neutral chamber of the dry pipe valve, a valve controlling the latter connection, a sliding latch, a pivoted elbow lever connected to said latch and to said sylphon, a pivoted weight-supporting member normally engaging said latch, and a weight supported by said member, whereby when the pressure between the chambers becomes unbalanced the expanding action of the sylphon withdraws the latch from the weight-supporting member allowing the weight to fall and open the valve in the connection leading to the neutral chamber of the dry pipe valve.

4. An accelerator for a dry pipe valve comprising a chamber normally containing fluid under pressure and provided with a communication leading to the neutral chamber of a dry pipe valve, a valve normally closing said communication, a weight which by its falling movement opens the valve, a pivoted weight-supporting member on which the weight is supported, a sliding latch normally engaging said member and holding the weight raised, and means rendered operative by a slight rapid reduction of pressure in the system to withdraw said latch from said support and allow the weight to fall.

50 In testimony whereof, I have signed my name to this specification.

FRANCIS H. GRIFFITHS.
